UNITED STATES PATENT OFFICE.

HENRY BURLICH AND GREGOR WALZEL, OF NEW YORK, N. Y.

ZINC BED FOR PRINTING PURPOSES.

SPECIFICATION forming part of Letters Patent No. 637,920, dated November 28, 1899.

Application filed February 7, 1899. Serial No. 704,866. (No model.)

To all whom it may concern:

Be it known that we, HENRY BURLICH and GREGOR WALZEL, citizens of the United States, residing at New York, in the county 5 of New York and State of New York, have invented certain new and useful Improvements in Zinc Beds; and we do hereby declare the following to be a clear and exact description of the invention, reference being had to the accompanying drawings, which form part of this specification.

Our invention relates more particularly to zinc beds which are used in lithographic-printing machines, and has for its object to provide 15 novel and simple means to stretch a sheet-zinc over the bed in a perfect manner and also to render same easily detachable from the bed.

For this purpose our invention consists in 20 certain peculiar and novel features of construction and arrangements, as hereinafter set forth.

In order that our invention may be fully understood, we will proceed to describe it with 25 reference to the accompanying drawings.

Figure I represents a sectional view of the zinc bed as it appears with all appliances removed. Fig. II represents a sectional view of the frame bearing the sheet-zinc, and Fig. 30 III represents a sectional view of the zinc bed with all appliances assembled.

Similar letters refer to similar parts throughout the several views.

Fig. I represents a sectional view of the zinc bed proper, in which A designates a cast-iron box, rectangular in shape, provided with a flange f near the top and lugs l, conveniently placed at the bottom to suit the traveling bed of a printing-machine. The flange f is beveled off at c. Webs w are suitably placed to strengthen the structure and the spaces between said webs perforated with a number of very small holes h, the general arrangement of same being such as shown. Another feature of the zinc bed consists of openings o, tube-like in shape t, forming part of the body of the box and projecting some distance into the hollow space of the same.

Fig. II, a sectional view, represents a square frame F, fitting the top part of the box A above the flange f, preferably made of wood and beveled off at the bottom d. Z designates

a sheet-zinc provided with grooves g, which engage into the corresponding grooves g at the top of the frame F. The sheet-zinc 55 is bent around the frame and turned into the beveled part of the frame to be fastened there. The space between the sheet-zinc and the frame has been made air-tight.

Referring to Fig. III, which is a sectional view of the zinc bed with all the parts assembled, p designates a plunger, s a spindle threaded, turned down at n, and which, entering a bearing k, designed to be easily removed, will be firmly located by a collar r. 60 The projecting part of the spindle s i is made square to receive the socket of a lever. The plunger p is provided with an elongated part e, which, being threaded, is designed to act like a nut for the spindle s.

v represents an air-valve of the ordinary type as such are used in air-pumps.

The method of using this zinc bed is the following: The sheet-zinc, secured to the frame in the manner described, and thus 75 forming one piece, after being properly treated and ready to print from is placed on the top of the bed, Fig. III, and the space between the beveled-off parts d c filled then with a suitable material, such as wax, thus rendering 80 the bed air-tight.

The application of an air-pump creating a vacuum in the hollow part of the bed, and thereby causing a pressure on the sheet-zinc, will spread same absolutely flat.

To facilitate the process of creating a vacuum, we fill the bed with a liquid. It is readily understood that a few strokes of the air-pump will suffice to obtain the desired pressure, which can be modified according to 90 wants by turning the spindles s, which engage into the plungers p, thereby increasing or decreasing the hollow space of the bed, according to the direction of the motion imparted to the plungers, thus changing the 95 pressure originally obtained.

Having now fully described our invention, what we claim as new, and desire to secure by Letters Patent, is—

1. In a zinc bed for printing purposes the 100 combination with a detachable frame bearing the sheet-zinc and designed to render said frame air-tight to the body of the zinc bed, substantially as described.

2. The combination of a frame provided with grooves at the top, and beveled off at the bottom, with a sheet-zinc thereon provided with grooves, said grooves engaging in grooves of said frame and fastened to same substantially as described.
3. In a zinc bed, a cast-iron box, perforated at the top and having a beveled flange, said box being provided with lugs, air-valves, plungers, and openings to receive and means

to operate the plungers, substantially as described.

In testimony whereof we have set our names in the presence of two subscribing witnesses.

HENRY BURLICH.
GREGOR WALZEL.
